POULTRY FEEDER PIPE SUPPORT

Gerald L. Kitson, 9709 Belding Road,
Rockford, Mich. 49341

Filed July 6, 1971, Ser. No. 160,245

Term of patent 14 years

Int. Cl. D8—08

U.S. Cl. D8—235

FIG. 1

FIG. 2

FIG. 3

FIG. 4

FIG. 1 is a perspective of a poultry feeder pipe support embodying my new design and associated with a segment of feed pipe and trough, the segment being in broken line to illustrate the environment.

FIG. 2 is an end elevation of the poultry feeder pipe support embodying my new design.

FIG. 3 is a top view of the poultry feeder pipe support shown in FIG. 2.

FIG. 4 is a bottom view of the poultry feeder pipe support shown in FIG. 2 and FIG. 3.

I claim:

The ornamental design for poultry feeder pipe support, as shown and described.
